UNITED STATES PATENT OFFICE

GEORGE C. QUELCH, OF OAKMONT, PENNSYLVANIA, ASSIGNOR, BY MESNE ASSIGNMENTS, TO UNION CARBIDE AND CARBON RESEARCH LABORATORIES, INC., OF NEW YORK, N. Y., A CORPORATION OF NEW YORK

TIP FOR CUTTING TORCHES

Application filed September 28, 1928. Serial No. 309,025.

My invention refers to an improvement in the class of torches for the cutting of ferrous metals. The present invention refers more particularly to means for effecting a more 5 thorough mixture of the combustion gases with oxygen in the tip member of the torch prior to delivery, for preheating. One preferred embodiment of the invention is herein illustrated and further described.

10 In such torches, which are now in large and common use, a preheating flame of high temperature is first directed against the metal to be cut, and, when the combustible temperature of the metal is reached, a jet of pure 15 oxygen under pressure is directed against the oxygen under pressure is directed against the heated portion, with a corresponding continuation of the preheating flame.

Combustion of the metal, under the oxygen jet, then occurs, reducing the metal to magnetic oxide of iron, the pressure jet of oxygen forcing the oxide through and away from the narrow curf made in the metal as the cutting action proceeds along a given line.

In torches of this general class, the device 25 is usually provided with three supply pipes or conduits, leading to the terminal head embodying the tip, providing for the supply of high pressure oxygen for cutting, low pressure oxygen, and a combustible gas for 30 burning therewith, for preheating.

The present improvement has in view to utilize higher pressures of the combustion gases, with consequently higher resulting velocities, partly by the use of restricted 35 passages and orifices through which the gases pass and become very thoroughly mixed.

The general objects in view are to secure a more intimate and combined mixture of fuel gas and oxygen between the burner tip 40 and its surrounding shell, and to deliver a preheating mixture of even consistency and uniform pressure, at a desired speed of supply. Also to so construct the tip as to make it adaptable for utilization and incorporation in standard makes of cutting tools in which the supply of oxygen and fuel gas is effected in the head of the torch or between the fuel and oxygen supply valves and the torch head.

50 In the drawings:

Fig. 1 is a sectional view of the head of a conventional form of cutting torch provided with my improved tip;

Fig. 2 is a plan view of Fig. 1;

Fig. 3 is a diagonal vertical section on the line III—III of Fig. 2;

Fig. 4 is a diagonal cross section on the line IV—IV of Fig. 3;

Fig. 5 is a sectional detail view of the tip and its shell, detached;

Figs. 6, 7 and 8 are cross sections on the lines VI—VI, VII—VII and VIII—VIII respectively of Fig. 5;

Fig. 9 is an enlarged longitudinal section of the mixer, detached.

Referring to the drawings, A is the head of a standard torch, having the usual high pressure oxygen pipe 2, a low pressure oxygen pipe 3, and a gas supply pipe 4 communicating with the several corresponding passages 5, 6 and 7.

These several conduits are controlled by valves of well known construction and function, not necessarily shown.

As is generally understood in the art, the 75 preheating mixture is effected by mixing the low pressure oxygen from port 6 with the preheating gas, as acetylene, hydrocarbon, etc., passing from channel 7 to delivery passages surrounding the central oxygen combustion supply passage 8 of the burner tip a.

The head A is provided with an annular chamber 10 surrounding the tip member within the head and communicating with the mixer furnished supply of gas and oxygen 85 from ports 6 and 7.

The mixer, which may be of any suitable construction, is in the present case similar to that shown and described in a companion application filed Sept. 28, 1928, Ser. Number 309,026, which has resulted in Patent No. 1,745,190, issued January 28, 1930.

It is mounted at one side of the head within a projecting enlargement 11 thereof, preferably made integral with the head casting, 95 and providing a continuous channel leading inwardly to the annular chamber 10 at an angle to the general line of the several supply pipes and conduits, as in Fig. 4.

Intervening between its ends, such channel, 100

i. e., the inner wall of enlargement 11, is provided with a screw-threaded mounting 12, at each side of which are the outer annular channel 13 and the inner annular channel 14 respectively. These communicate with the preheating oxygen pipe 3 by channel 6, and the gas pipe 4 by channel 7 respectively.

The jet member α is so constructed and mounted as to function in the manner generally followed by torches of the kind involved, and to deliver a preheating flame through the several outer channels prior to combustion of the metal by the cutting oxygen through central channel 8.

15 The mixer, as shown, is mounted within the communicating channel 13-14 referred to, by threaded engagement with the threads 12 at the middle portion of an outer shell member 15.

20 Said member, as shown, is hollow at its inner end beyond the solid shank portion 16 having the screw or bolt head 17 for tightly inserting it in position, with an intervening packing gasket 18.

25 Inserted centrally in the hollow portion of the mixer part way back from its delivery end is an inner tube 19 having a central bore 20 at its inner portion communicating by a central port 21 with the several lateral oxygen inlet ports 22 for supply of oxygen from pipe 3 through channel 6, as more fully shown in said application.

At its inner or delivery end tube 15 is provided with a very small central outlet delivery port 23 and with similar small oxygen outlet ports 24, both communicating with a central longitudinal larger channel 20 which is in constant communication with the oxygen supply from port 6.

40 Inwardly beyond the middle screw-threaded barrel portion 25 of tube 15 is an annular space 26 between the central tube 19 and the outer shell 15, through which passage fuel gas passes toward the delivery end of the mixer. Shell 15 is provided, between its threaded portion and the delivery end, with a series of transverse fuel gas inlet ports 27 communicating with chamber 14 and port 7 for inward supply of gas from pipe 4.

55 The tip α is preferably made of one piece having the forward tapering end 28 fitting within and surrounded by the shell 29 and tapped into the head by its inner threaded terminal 30.

55 Shell 29 makes a snug fit within the delivery portion of head A and is secured by the customary nut 31, with oxygen port 8 in communication with supply port 5. The inner portion 32 of the tip and its outer portion 60 33 fit tightly within the surrounding shell 29, sufficiently close to prevent the passage between them of any gases.

Between such contacting shoulders 32 and 33 the intervening shank portion of the tip 65 is provided with variable diameter portions

34-35-36, providing annular mixture chambers of alternating size.

As shown, the space between the tip body and the shell is reduced or throttled from 36 to 35, and then increased from 35 to 34, whereby gases entering from the rear may pass longitudinally and annularly, with such intervening partial opposition and subsequent opportunity for expansion.

Beyond the annular reduced neck 34, a series of emission slots 37 extend longitudinally of the terminal portion of the tip, whereby to deliver mixed gases outwardly around the central oxygen outlet and into the extremity of the shell, for discharge therefrom. Slots 37 extend backwardly sufficiently far beyond annular shoulder 33 to provide for circulation of gases outwardly from the last annular mixing chamber of the series.

85 For the purpose of introducing oxygen and gas to the first of such series of annular mixing chambers from chamber 10 of the head, I provide a holding key 38, between the tip and its shell, with a longitudinal circulating port 39.

90 Said port, which is of the proper size to admit the mixture to the interior annular spaces in the proper amount and dependent on the pressure of the gases used, has a free inlet and outlet clearance in the opposite ends of the keyway, as clearly shown.

95 Said port, which is of the proper size to admit the mixture to the interior annular spaces in the proper amount and dependent on the pressure of the gases used, has a free inlet and outlet clearance in the opposite ends of the keyway, as clearly shown.

As thus constructed and mounted in the head, the oxygen supplied from the usual preheating pipe 3 and gas supplied through pipe 4 are not only brought into a preliminary mixed condition in chamber 10, but are further intimately mixed within the several annular comparatively shallow chambers surrounding the variable necks 36, 35 and 34.

100 By reason of the alternating width of these film-forming chambers, the volume of the mixture therein is subjected to the rear pressure and a forward partial resistance, so that in passing along through the tip, the elements of the mixture will be very thoroughly and intimately commingled.

105 By reason of such construction and arrangement, the pressure of the fuel gases may be increased, with increased pressure of the preheating oxygen supply, so that the effect of the preheating mixture in the torch, with better mixing and higher pressures, is greatly improved.

110 It will be understood that the number of the several variable annular chambers, their degree of difference in width, and the size, proportions and other features of detail construction of the invention may be variably changed or modified by the skilled mechanician in making or utilizing the invention, and that all such changes are to be understood as within the scope of the following claims.

115 What I claim is:—

1. A burner tip for cutting torches provided with a central oxygen port and having a separately inserted perforated member providing a lateral inlet combustion gas port, a substantially longitudinal delivery port, and a series of intervening annular channels. 70
2. A burner tip for cutting torches provided with a central oxygen port and having at its rear end a laterally arranged keyway and a perforated key therein providing an inlet combustion gas port, at its front end a longitudinally arranged delivery port, and a series of intervening annular channels. 75
3. A burner tip for cutting torches provided with a central oxygen port and having at its rear end a laterally arranged perforated key providing an inlet port and a longitudinally arranged delivery port at its front end, and a series of annular channels between said ports. 80
4. A burner tip for cutting torches provided with a central oxygen port and having at its rear end a laterally arranged perforated key providing an inlet port and a longitudinally arranged delivery port at its front end, and a series of variable diameter reduced sections between the inner and outer end of the tip providing annular mixing chambers. 85
5. In combination with a burner head having a cutting oxygen supply port and a combustible gas cavity, a burner tip having a central port communicating with the cutting oxygen supply and a surrounding shell inserted in the head and provided with an inner lateral port opening into the gas cavity, an outer lateral port covered by the shell, and a series of annular intervening variable diameter reduced portions within the shell. 90
6. In combination with a burner head having a cutting oxygen supply port, a combustible gas cavity, and a supplemental extended shell, a burner tip within the shell having a central oxygen port, a perforated key engaging a keyway in the burner tip and in the shell, a series of terminal delivery slots, and an annular reduced neck at the middle portion of the tip providing a mixing cavity within the shell. 95
7. In combination with a burner head having a cutting oxygen supply port, a combustible gas cavity, and a supplemental extended shell, a burner tip within the shell having a central oxygen port, a perforated key engaging a keyway in the burner tip and in the shell, a series of terminal delivery slots, and an annular reduced neck at the middle portion of the tip communicating with the delivery slots and providing a mixing cavity within the shell. 100
8. In combination with a burner head having a cutting oxygen supply port, a combustible gas cavity, and a supplemental extended shell, a burner tip within the shell having a central oxygen port, a perforated
- key engaging a keyway in the burner tip and in the shell, a series of terminal delivery slots, and a series of variable diameter annularly reduced portions between the ends of the tip providing supplemental mixing chambers within the shell, the outermost chamber communicating with the delivery slots. 105
- In testimony whereof I hereunto affix my signature.
